FRAME FOR WIRE MESH FABRIC

Filed Sept. 17, 1935

UNITED STATES PATENT OFFICE

2,111,448

FRAME FOR WIRE MESH FABRIC

Charles J. Hoffman, York, Pa.

Application September 17, 1935, Serial No. 40,970

3 Claims. (Cl. 189—84)

This invention relates to improvements in frames of the type used for forming rigid panels from woven or other wire fabric, expanded or perforated metal, or from metal sheets or other sheet materials of rigid or semi-rigid nature, and a principal object of the invention is to provide a frame of this character that shall be characterized by simplicity of form, relatively high efficiency and ornamental appearance.

Another object of the invention is to provide a frame in which the wire mesh or other material may be securely confined without the requirement for rivets, bolts or extra securing elements.

Still another object of the invention is to provide a frame of novel form facilitating and reducing the cost of the operations of constructing the panel.

The invention further contemplates the provision of a basic frame element adapted to interlock efficiently with the wire mesh or other material in such manner that the interlocking grip increases in efficiency with any pressure imposed upon the wire or other material tending to draw the latter from the frame.

Still another object is to provide a frame that shall be highly adaptable to different characters of panel, as hereinafter set forth.

In the attached drawing:

Figure 1 is a fragmentary view in perspective of a portion of a panel made in accordance with my invention;

Fig. 2 is a section on the line 2—2, Fig. 1;

Fig. 3 is a view showing a completed panel;

Fig. 4 is a view in perspective of a modified form of corner plate within the scope of my invention;

Figs. 5 and 6 are sectional views showing modified forms of the basic frame element;

Figs. 7 and 8 are fragmentary face views of the elements shown respectively in Figs. 5 and 6, and

Figs. 9 and 10 are fragmentary sectional views illustrating, respectively, the mode of operation of the frame elements shown in Figs. 5 and 6.

With reference to the drawing, the frame comprises a basic element in the form of a hollow bar 1 preferably of rectangular cross section. This bar, which can conveniently be made of metal, is divided longitudinally in one face, and the portions 2 of the bar adjoining the split are turned inwardly at an angle. The bar may be made in stock lengths and divided longitudinally in sections of the various lengths required for panels of different sizes.

The space between the free edges of the inturned portions 2 is dimensioned to receive the wire mesh or other panel material, as shown in

Figs. 1 and 2, and so that the said edges of the portions 2 will bear snugly against the opposite sides of the said material. By reason of the resiliency of the material of which the bar is formed, the receiving slot may be made somewhat smaller than the effective thickness of the panel material, and the resiliency affords a certain leeway for accommodation of different thicknesses.

While the bar may be used with materials of various characters, it is well adapted for use with 10 mesh of the diamond type, as illustrated in Figs. 1 to 3. The individual strands of this wire fabric are crimped, so that the effective thickness of the fabric varies. In assembly, the opposed edges of the portions 2 of the frame, by engaging the 15 portions of the mesh of relatively small effective thickness as shown in Fig. 2, interlock securely with the fabric, so that the free edge portions of the latter are held securely in the bars. Under these conditions, it is apparent that any force 20 tending to withdraw the mesh from the frame, except in a direction longitudinally of the latter, will have a tendency to draw the free edges of the portions 2 of the frame bar together, thereby causing them to bind more securely against the 25 opposite sides of the wire fabric. It accordingly is unnecessary with a frame constructed in accordance with my invention to employ any extra means such as rivets or welding to hold the wire fabric in the frame, and the assembling operation is, therefore, materially simplified and the 30 cost thereof reduced.

In producing a simple panel using the afore-described frame elements, the wire fabric is cut to size and four sections of the bar stock 1 are interlocked with the edges of the fabric by passing the fabric longitudinally into the slot between the portions 2, 2. This brings the frame bars 1 into abutment, and the bars are then united by means of corner plates 3. The plates 3 are of angular 35 form to conform with the angle between the adjoining ends of the bars 1 and embrace the side faces of the adjoining bars and the surfaces of the latter extending inwardly to the outer edges of the inturned portions 2. Each of the plates 40 3 is also provided at its inner edge with a flange 4, which in assembly lies more or less snugly against the face of the wire fabric and which not only improves the appearance of the panel but which also functions as a strut to reinforce the 45 corners of the frame. Preferably and as illustrated, two of these plates 3 are used at each corner of the frame and at opposite sides thereof, and they are united to the bars 1 and to each other preferably by means of rivets 5 which may 50 55

extend completely through the bars 1, as shown in Fig. 2. In this manner, a rigid frame of great strength is afforded in which the wire fabric is securely clamped.

5 The frame construction described above is highly adaptable to the production of many different types of panel and presents a highly desirable and finished appearance. In Fig. 3, I have illustrated a panel of which the upper portion 6 consists of the wire mesh, while the lower portion 7 is composed of a solid sheet of metal or other suitable material. This sheet is confined in the frame in the same manner as the wire fabric and as described above. The side frame pieces 10 8, 9 in this case extend continuously from the top of the panel to the bottom, and four cross bars 9 are employed secured to the members 8 by corner plates 3 as described. It is obvious that in a construction such as this, the intermediate 15 angle plates 3 may be replaced by plates 3a of the general form illustrated in Fig. 4.

In Fig. 5, I have illustrated a modification of the basic frame element shown in Fig. 1. This element is adapted primarily for use with panel 25 sheets of perforated metal. The frame element 1a is constructed on essentially the same principle as the element 1 previously described, but in this case the lip portions 2a are provided with more or less intermeshing teeth 10 which in assembly and as shown in Fig. 9 are adapted to project into the perforations 11 of the perforated sheet 12, thereby interlocking the frame with the perforated panel sheet.

A somewhat similar embodiment of the invention is illustrated in Figs. 6, 8 and 10. In this case, the lips 2b of the frame element 1b are provided with series of small teeth 13 which in assembly and as shown in Fig. 10 are adapted to interlockingly engage the panel material 14. This 30 form of frame element is adapted primarily for use with solid panel materials of the composition or plaster-board type.

It will be apparent that the frame elements shown in Figs. 5 and 6 embody the same basic principle as that disclosed in Fig. 1, and there 45 may be still further modifications without departure from this principle.

I claim:

1. As a new article of manufacture, a hollow sheet metal frame member of box section, said metal being inherently resilient and of a gauge

conferring substantial rigidity upon said member, said member being slotted longitudinally in one face thereof and the metal adjoining each side of the slot being turned inwardly at an angle to the normal plane of the slotted face and forming angularly converging lips the free edges of which define the sides of the slot, said lips being adapted to engage at their free edges the opposite faces of a panel member inserted in the slot and being adapted when said panel member is placed under tension at the center to flex toward each other and to thereby clamp the panel with increasing pressure in proportion to the degree of said tension.

2. As a new article of manufacture, a hollow frame member adapted for assembly in end to end relation with hollow members of like form to produce said frame, said member having in the wall thereof a slot extending continuously from one end of said member to the other for reception of a mesh or other panel element, the portions of said wall adjoining the opposite sides of said slot extending convergently inward and at an angle to each other so that their free edges define the relatively narrow mouth of the slot and so that the contact between said member and the panel element may be restricted substantially to said edges, said member being substantially rigid and being composed of a material having sufficient inherent resilience to permit the said convergent portions to bear resiliently at their said free edges against the opposite sides of said panel element and to flex toward each other when the panel element is placed under tension to thereby increase the bearing pressure of said free edges against the panel element.

3. In a frame, a side member having a longitudinal slot for reception of an edge portion of a panel element, the portions of said member adjoining the opposite sides of said slot each extending rearwardly from the normal face of the member and forming angularly convergent lips, the free edges of which define the sides of the slot, said lips being adapted to engage at their free edges the opposite faces of the panel element and being adapted when said element is placed under tension at the center to flex toward each other and to thereby clamp the panel with increasing pressure in proportion to the degree of said tension.

CHARLES J. HOFFMAN.
